FIG. 1 is a perspective view of a covered casserole dish or the like showing our new design;

FIG. 2 is an elevational view, partly in section;

FIG. 3 is a top plan view;

FIG. 4 is a perspective view with the cover member in position as a base;

FIG. 5 is an enlarged scale elevational view of the cover member; and

FIG. 6 is an elevational view, partly in section, of FIG. 4.

The essential feature of the design not only resides in the particular ornamental band applied to the shallower member, but also in the specifically shaped casserole combination disclosed.

We claim:

The ornamental design for a covered casserole dish or the like, as shown and described.
